[57] CLAIM

The ornamental design for a self-powered drogue light, substantially as shown and described.

DESCRIPTION

FIG. 1 is a right side elevation view, partially broken away, of a self-powered drogue light showing the new design;

FIG. 2 is a front elevation view thereof;

FIG. 3 is a bottom plan view thereof;

FIG. 4 is a rear elevation view thereof;

FIG. 5 is a top front perspective view thereof; and

FIG. 6 is a top rear perspective view thereof.

A left side elevation view thereof is the mirror image of FIG. 1. A top plan view thereof is the mirror image of FIG. 3.

FIG. 1

FIG. 2

FIG. 3

FIG. 4

FIG. 5
